UNITED STATES PATENT OFFICE.

AUGUSTE ARTHUR CAILLE, OF DETROIT, MICHIGAN.

DESIGN FOR A CASING FOR COIN-ACTUATED MACHINES.

SPECIFICATION forming part of Design No. 37,489, dated July 11, 1905.

Application filed May 27, 1905. Serial No. 262,687. Term of patent 7 years.

To all whom it may concern:

Be it known that I, AUGUSTE ARTHUR CAILLE, a citizen of the United States of America, residing at Detroit, in the county of Wayne and State of Michigan, have invented a certain new, original, and ornamental Design for a Casing for Coin-Actuated Machines, of which the following is a specification, reference being had therein to the accompanying drawing, forming a part thereof, in which—

My new design is shown in perspective view.
I claim—

The ornamental design for casing for coin-actuated machines as shown.

AUGUSTE ARTHUR CAILLE.
